UNITED STATES PATENT OFFICE.

WILLIAM E. FISSEL, OF YORK COUNTY, PENNSYLVANIA.

CHICKEN-COUNTING DEVICE.

Application filed June 17, 1925. Serial No. 37,729.

This invention relates to a counting device for fowl. The object of this invention is to provide a device which will count and indicate the number of chickens which have 5 entered or left the roost. A particular object in connection with this device is to provide an arrangement which will scare a second chicken from attempting to pass through the same before the first has completed the manipulation necessary for operating the counter. In this way two chickens will not pass through the device and be registered only as one. Simplicity and cheapness of construction are other objects of this 15 invention so far as they may be consistent with durability.

Other objects will be apparent, and this invention will be more fully understood from the following description, taken in 20 connection with the accompanying drawing which form a part hereof.

The figure in the drawing represents one form of device which forms the subject matter of this invention. 25 With reference to the drawing, 1 is a base board to which is fixed two side boards 2 and 3. A cross board 4 braces and connects the upper ends of the side boards 2 and 3. A gate 5 is hinged to the side board 3 and 30 arranged to open only in the direction indicated by the arrow 6. A tilting platform 7 is carried by the cross rod 8, and arranged to normally tend to tip in the direction indicated by the arrow 9, this of course may 35 be arranged through the proper location of the rod 8; the front end 10 of the platform in this case being heavier than the rear end 11. The cross rod 8 in this particular case is carried by the side boards 2 and 3, and 40 should be fixed thereto in any obvious manner which will permit tipping of the platform 7.

A connecting rod 15 is provided as shown, the one end thereof being connected to the 45 platform 7 through the screw eye 12, and the opposite end to the gate 5 through the screw eye 14. Through these connections it is apparent that movement of the gate must work in unison with movement of the platform, viz;—if the gate is caused to open in the direction indicated by the arrow 6, the platform will tip in the direction indicated by arrow 16; or if the platform is tipped in the direction indicated by the arrow 16 55 the gate will open in the direction indicated by arrow 6. It is to be observed that

due to the platform 7 being heavy on the end 10, and thereby tending to move in the direction indicated by arrow 9, the gate 5 is thereby automatically closed and normally held closed. 60

The space between the edge 17 of the gate and the side board 2 must be smaller than that required for a chicken to pass through, and when arranged in this manner a chicken 65 cannot pass through the device in the direction indicated by arrow 18; it is therefore a one-way device in that a chicken can pass through only in the direction indicated by arrow 19. The fact that there is a space between the edge 17 of the gate and side board 2, serves as an inducement for a chicken to pass through, and the screened portion 20 of the gate also serves this purpose. 70

When a chicken passes through the device in the direction indicated by arrow 19, it may or may not step upon the platform 7, that is to say it may attempt to squeeze through the space between the edge 17 of 80 the gate and the side board 2 and may in some manner avoid stepping upon the platform. The gate will then of course open and let the chicken through, but the movement of the gate will also tip the platform. 85 This tipping of the platform will normally scare any other chicken which may attempt to pass through at the same time or at least until the gate has slammed shut. However, normally the chicken will step upon the platform at 27, and it will tip in the direction, indicated by arrow 16 and open the gate, and of course scare any other chicken which may attempt to pass through at the same time. It is to be observed 95 that the side board 2 extends somewhat beyond the closed position of the gate, as indicated by the numeral 30. The object of this is to make it more difficult or utterly improbable that a chicken can get 100 back of the gate sufficiently to open the same if it should attempt to pass through the device in the direction indicated by arrow 18, and in this manner register a false count.

What has here been said with reference 105 to chickens of course also applies to any fowl, such as pigeons, ducks, geese, etc., or to nearly any kind of live stock which would be scared or in some similar manner be affected by the tipping of the platform. 110

The registering is accomplished through the counting device mounted upon the cross

board 4; which comprises a toothed wheel 21 which is free to turn on the round head screw 22 and arranged to register the hundreds; and a unit wheel 23 which is free to turn on the round head screw 24. The unit wheel 23 is provided with a tooth 28 which is arranged to engage the teeth in the wheel 21, and move the same one notch, indicating one hundred, in each revolution thereof.

10 It is of course to be understood that this device is to be fitted in the partition or wall of the coop. As an example I have shown a wire screen 29 separating the entrance side of the device from the exit side, and which 15 in effect is a partition. This device in itself forms a sort of door frame or alley-way.

Having thus described my invention what I claim and desire to secure by Letters Patent is as follows:

20 1. In a counting device for fowl, the combination with a tiltable platform, of a fulcrum arranged to carry said platform in a manner whereby the front end thereof normally tends to fall through the influence of 25 gravitation, a door frame at the rear end of said platform, a door in said door frame and arranged to open horizontally only in

one direction, which direction is away from said platform and also arranged to only partially close said door frame, and a connecting link arranged to connect said platform to said door in such manner whereby the normal tendency of the front end of said platform to fall, will draw said door to its closed position, and rest with the front end thereof elevated relative to the rear end thereof. 30 35

2. In a counting device for fowl, the combination with a tiltable platform, of a fulcrum arranged to carry said platform in a manner whereby the front end thereof normally tends to fall through the influence of gravitation, a door frame at the rear end of said platform, a door in said door frame and arranged to open only in one direction, 40 45 which direction is away from said platform, and a connecting link arranged to connect said platform to said door in such manner whereby opening movement of the door will cause the front end of said platform to rise 50 against its normal tendency to fall.

In testimony whereof I affix my signature.

WILLIAM E. FISSEL.
